(57) **CLAIM**

What is claimed is the ornamental design for a folding urinal, as shown and described.

DESCRIPTION

FIG. 1 is a front perspective view of the folding urinal with its folding tray closed;

FIG. 2 is a front view of the folding urinal with its folding tray closed;

FIG. 3 is a rear view of the folding urinal with its folding tray closed;

FIG. 4 is a right side view of the folding urinal with its folding tray closed;

FIG. 5 is a left side view of the folding urinal with its folding tray closed;

FIG. 6 is a top view of the folding urinal with its folding tray closed;

FIG. 7 is a bottom view of the folding urinal with its folding tray closed;

FIG. 8 is a front perspective view of the folding urinal with its folding tray open;

FIG. 9 is a front view of the folding urinal with its folding tray open;

FIG. 10 is a rear view of the folding urinal with its folding tray open;

FIG. 11 is a right side view of the folding urinal with its folding tray open;

(Continued)

FIG. 12 is a left side view of the folding urinal with its folding tray open;

FIG. 13 is a top view of the folding urinal with its folding tray open; and,

FIG. 14 is a bottom side view of the folding urinal with its folding tray open.

The broken lines shown in the drawings are for purposes of illustrating portions of the design and form no part of the claimed design.
